UNITED STATES PATENT OFFICE.

WILLIAM H. BIDINGER, OF OTTUMWA, IOWA, ASSIGNOR OF ONE-HALF
TO JOHN H. RHEEM, OF OTTUMWA, IOWA.

RAILWAY-SWITCH.

No. 798,991.

Specification of Letters Patent.

Patented Sept. 5, 1905.

Application filed April 8, 1905 Serial No. 254,582.

To all whom it may concern:

Be it known that I, WILLIAM H. BIDINGER, of Ottumwa, in the county of Wapello and State of Iowa, have invented certain new and useful Improvements in Railway-Switches; and I do hereby declare that the following is a full, clear, and exact description thereof, reference being had to the accompanying drawings, and to the letters of reference marked ⁵ thereon, which form a part of this specification.

This invention relates to improvements in switch equipments for railway-tracks for diverting a car or cars from a main track to a ¹⁵ branch track, and vice versa, and refers more specifically to switches adapted for use in mines for switching coal or ore cars from the main track or tramway to branch tracks leading to the different rooms of the mine at the side of ²⁰ the main track.

Among the objects of my invention is to simplify and reduce the cost of such switch equipments and to reduce the cost of time and labor required for removing or changing a ²⁵ switch from one point to another.

A further object of the invention is to provide a switch equipment of this character which is capable of being removed entirely from the main track and which may be applied to the main track without the use of ³⁰ switch-frogs or the like or otherwise mutilating the rails of the main track.

A still further object of the invention is to minimize or entirely avoid the tendency of ³⁵ loaded cars being derailed as they pass from the branch track to the main track over the switch.

The invention consists in the matters hereinafter set forth, and more particularly pointed out in the appended claims.

In the drawings, Figure 1 is a plan view of a section of the main track, showing a branch track and my improved switch equipment for connecting the same. Fig. 2 is a transverse section taken on line 2 2 of Fig. 1. Fig. 3 is a transverse section taken on line 3 3 of Fig. 1. Fig. 4 is a fragmentary inside view of the inside or short rail of the switch and the associated main-track rail, showing the taper thereof by ⁴⁵ which the car-wheel flange is raised above the main-track rail. Fig. 5 is an enlarged detail section taken on line 5 5 of Fig. 1.

As shown in the drawings, A A designate

the rails of the main track, and A' the cross-ties thereof.

55

B B designate the rails of the branch track, which in mining use lead to a room in the mine located at one side of the main track, and B' the ties thereof.

My improved switch for connecting the ⁶⁰ branch track with the main track consists of two curved rails C C', which are connected to their supports at points at the side of the main track in a manner to be entirely removed from the main-track rails when not in use and ⁶⁵ to be swung into their switching positions in a manner to guide a car from the main to the branch track, or vice versa, without cutting or mutilating the rails of the main track. As ⁷⁰ herein shown, the outer ends of said switch-rails are hinged to their supports in a manner to be swung laterally on their hinges to the positions shown in dotted lines in Fig. 1.

The outer curved rail C extends over the inner rail of the main track and diagonally ⁷⁵ across the track and lies at its free end upon the outer rail of the main track, and the shorter curved rail similarly lies at its free end upon the inner rail of the main track. The free ends of said curved switch-rails, ⁸⁰ which so lie upon the rails of the main track, are beveled or inclined on their upper faces, as shown at e e', so as to facilitate the passage of car-wheels from the main track to the said switch. The switch-rails are made of rec- ⁸⁵

tangular cross-section and of greater height than the depth of the flanges of the wheels of the car used thereon. The free end of the shorter curved switch is so inclined as to raise the flange of the car-wheels above the ⁹⁰ inner rail of the main track at the point where the said inner curved rail crosses said inner main-track rail, whereby the car-wheels cross the inner rail of the main track without contact of the wheel-flanges therewith. ⁹⁵ The longer curved switch-rail is of its full cross-sectional dimensions at the point where it crosses the inner rail of the main track, thereby similarly preventing contact of the wheel-flanges with the said main-track rail ¹⁰⁰ when the cars cross the same.

The hinged switch-rails are supported at their outer ends upon extension-ties D D', which, as herein shown, extend beneath the rails of the main track, as shown at d, and ¹⁰⁵ extend laterally from said track toward the

branch track. The switch-rails are shown as hinged at their outer ends to the ends of short rail-sections E E, which are supported by said extension-ties D D. The outer ends of the rail-sections E abut against the ends of the rails B of the branch track. Any suitable form of hinge connection between said rail-sections and the switch-rails may be provided that will permit the car-wheels to ride freely thereover. As herein shown, the adjacent ends of said rail-sections and the switch-rails are provided with overlapping extensions e e, respectively, Fig. 5, and they are hinged together by means of studs F, driven into the extension-ties, which extend upwardly through apertures in the extensions e and engage at their upper ends downwardly-opening sockets formed in the lower faces of the extensions e. The said overlapping extensions of the connecting-rails and switch-rails are beveled on their opposing faces, so as to permit the outer ends of the switch-rails to be raised from the main-track rails preparatory to swinging them outwardly from said main track in the position shown in dotted lines in Fig. 1. The rails B B of the branch switch-track may be joined to the connecting-rails at any suitable angle, either laterally or vertically, depending upon the location of the room to which the branch track leads.

Means are provided for locking the switch-rails from lateral displacement after the same have been adjusted to the main track. As herein shown, such locking means consists of downwardly-extending lugs c c near the free ends of said rails, which enter sockets g, formed between the main-track rails, and blocks G G, fastened to the ties at the sides of the main-track rails in any suitable manner. The longer curved switch-rail is supported between the rails of the main track by means of an oblique sleeper or block H, that lies upon the cross-ties A' and is fixed thereto in any suitable manner. As an additional precaution against lateral movement of said outer rail it is preferably provided with a second locking-lug c, and the sleeper is provided with a notch h, which receives the locking-lug. The swivel construction of the hinge due to the inclined faces of the overlapping extensions of the switch-rails and connecting-rails permits the switch-rails to be raised to release the locking-lugs from the locking devices preparatory to swinging the switch-rails off the main track. Preferably the shorter or inside curved rail is supported between its ends upon a block I, located at the side of the inner rail of the main track. The insertion of the extension-ties D beneath the main-track rails constitute a means of firmly anchoring said ties to the main track, and so far as the broader features of the invention are concerned said extension-ties

may be fixed firmly in place relatively to the main track in any other convenient manner.

It will be observed that the rails of the main track are not and need not be cut or otherwise mutilated, so that when the switch-rails are swung to one side of the track the main track is free and unobstructed and the travel of the cars thereover is facilitated. Furthermore, the absence of any frogs or special fittings for diverting the cars from the main track to the branch, and vice versa, avoids the tendency of derailment of the cars when passing from one track to the other. Another important advantage of my improved construction lies in the ease in which the switch may be applied to the main track and removed therefrom at a time when the branch track is to be removed from one room to another or from one point on the main track to another. In such case after the branch track is removed or partially removed the switch equipment may be readily taken up by removing the switch-rails and pulling the extension-ties from the main track and applying the same to the track at another point or location thereon. This operation requires but comparatively little time and labor, inasmuch as the switch-rails are not required to be fitted to the main-track rails by the use of switch-frogs or other special fittings.

Changes may be made in the structural details of the switch without departing from the spirit of my invention, and I do not wish to be limited thereto, except as hereinafter made the subject of specific claims.

I claim as my invention—

1. A railway-switch comprising, in combination with the main track and a branch track, two curved switch-rails which are hinged at their outer ends at one side of the main track to swing toward and from the main-track rails, and designed to be swung entirely away from the main track when not in use.

2. A railway-switch comprising, in combination with the main track and a branch track, two curved switch-rails which are hinged at their outer ends at one side of the main track to swing toward and from the main-track rails, and designed to be swung entirely away from the main track when not in use, and means for locking the switch-rails in switching relation to the main-track rails.

3. A railway-switch comprising, in combination with the main track and a branch track, two curved switch-rails hinged at their outer ends at one side of the main track to swing toward and from the main track, and designed to lie at their other ends upon the main-track rails, the ends of said curved rails, which lie upon the main-track rails, being inclined on their upper faces to facilitate the riding of car-wheels thereon.

4. A railway-switch comprising, in combination with the main track and a branch track,

two curved switch-rails hinged at their outer ends at one side of the main track to swing toward and from the main track, and designed to lie at their other ends upon the main-track 5 rails, the ends of said curved rails, which lie upon the main-track rails, being inclined on their upper faces to facilitate the riding of car-wheels thereon, and means for locking the switch-rails from lateral displacement on said 10 main-track rails.

5. A railway-switch comprising, in combination with the main track and a branch track, two curved switch-rails hinged at their outer ends at one side of the main track to swing 15 toward and from the main track, and designed to lie at their other ends upon the main-track rails, the ends of said curved rails, which lie upon the main-track rails, being inclined on their upper faces to facilitate the riding of car-wheels thereon, the rise or inclination of 20 the inner or shorter switch-rail being such as to clear the flange of the car-wheel of the main-track rail at the crossing of the short switch-rail over the main-track rail.

25 6. A railway-switch comprising, in combination with the main track and a branch track, two curved switch-rails hinged at their outer ends at one side of the main track to swing toward and from the main track and lying at 30 their other ends upon the rails of the main track, the longer rail extending transversely over the inner rail of the main track, and the free ends of said curved rails being inclined on their upper faces to facilitate the riding of 35 car-wheels thereon.

7. A railway-switch comprising, in combination with the main track and a branch track, two curved switch-rails hinged at their outer ends at one side of the main track to swing 40 toward and from the main track, and designed to lie at their other ends upon the main-track rails, the ends of said curved rails, which lie upon the main-track rails, being inclined on their upper faces to facilitate the riding of 45 car-wheels thereon, and locking-lugs at the free ends of said switch-rails adapted to enter sockets at the sides of the main-track rails to lock the switch-rails from lateral displacement.

50 8. A railway-switch comprising, in combination with the main track and a branch track, two curved switch-rails hinged at their outer ends at one side of the main track to swing toward and from the main track, and designed

to lie at their other ends upon the main-track 55 rails, the ends of said curved rails, which lie upon the main-track rails, being inclined on their upper faces to facilitate the riding of car-wheels thereon, locking-lugs at the free ends of said switch-rails adapted to enter 60 sockets at the sides of the main-track rails to lock the switch-rails from lateral displacement, the hinge for said switch-rails being constructed to permit vertical movement of the free ends of the switch-rails to release the 65 locking-lugs from said sockets.

9. A railway-switch comprising, in combination with the main track and a branch track, two curved switch-rails for connection with the main and branch tracks, ties extending 70 laterally from the main track and on which are supported rail-sections to which said curved switch-rails are hinged, the free ends of said switch-rails lying on top of the main-track rails and being inclined to facilitate the 75 riding of the car-wheels thereon, the hinge between said rail-sections and switch-rails comprising overlapping extensions on said parts and studs fixed to the extension-ties and engaging hinge apertures and sockets in said 80 overlapping extensions.

10. A railway-switch comprising, in combination with the main track and a branch track, two curved switch-rails for connection with the main and branch tracks, ties extending 85 laterally from the main track and on which are supported rail-sections to which said curved switch-rails are hinged, the free ends of said switch-rails lying on top of the main-track rails and being inclined to facilitate the 90 riding of the car-wheels thereon, the hinge between said rail-sections and switch-rails comprising overlapping extensions on said parts and studs fixed to the extension-ties and engaging hinge apertures and sockets in said 95 overlapping extensions, the adjacent faces of said overlapping extensions being beveled or cut away to permit the free ends of the rail-sections to be raised preparatory to swinging the same laterally. 100

In testimony that I claim the foregoing as my invention I affix my signature, in presence of two witnesses, this 29th day of March, A. D. 1905.
